Evelyn M. Dutton, New York, and Sol H. Pion,
Jamaica, N. Y.

Application January 22, 1949, Serial No. 384

Term of patent 7 years

(Cl. D3—26)

To all whom it may concern:

Be it known that we, Evelyn M. Dutton, a citizen of the United States, resident of 152 East 84th Street, city, county, and State of New York, and Sol H. Pion, a citizen of the United States, resident of 164-03 Hillside Avenue, Jamaica, county of Queens, State of New York, have invented a new, original, and ornamental Design for a Combination Slip and Brassière, of which the following is a specification, reference being had to the accompanying drawing, forming part hereof.

In the drawing:

Fig. 1 is a front view of a combination slip and brassière, showing our new design; and

Fig. 2 is a rear view of the combination slip and brassière, showing our new design.

We claim:

The ornamental design for a combination slip and brassière, substantially as shown.

EVELYN M. DUTTON.
SOL H. PION.
